UNITED STATES PATENT OFFICE.

RUSSELL S. WALKER, OF DULUTH, MINNESOTA, ASSIGNOR TO INFORMATION CABINET COMPANY, OF ST. LOUIS, MISSOURI, A CORPORATION OF DELAWARE.

DESIGN FOR A DISPLAY CABINET.

Application filed January 27, 1927. Serial No. 20,521. Term of patent 3½ years.

To all whom it may concern:

Be it known that I, RUSSELL S. WALKER, a citizen of the United States, residing at Duluth, in the county of St. Louis and State of Minnesota, have invented a new, original, and ornamental Design for Display Cabinets, reference being had to the accompanying drawing, forming part thereof.

I claim:

The ornamental design for a display cabinet, as shown.

RUSSELL S. WALKER.
